DRIVING ARRANGEMENT FOR THREAD
GUIDES, PARTICULARLY FOR COP WIND-
ING MACHINES

Albert Brügger, Horgen, Switzerland

Application December 14, 1942, Serial No. 469,034
In Switzerland November 13, 1941

8 Claims. (Cl. 242—46.2)

This invention relates to driving arrangements for thread guides, particularly for cop winding machines, provided with a gear drive having exchangeable reducing gears drivingly connected between the winding spindle and the traversing member of the thread guide.

According to the invention, a worm gear is arranged for cooperation with the exchangeable reducing gear drive.

In producing cops, recently the tendency to use crosswinds instead of parallel winds prevailed more and more for the purpose of avoiding eventual loosening of the thread coil as much as possible. Consequently, the latest development in the construction of cop winding machines follows this tendency. Since the production of crosswinds has above all the effect of reducing the velocity of winding, the employment of a back gear drive was resorted to with a view to minimizing this drawback in winding stronger, that is, more resistive thread materials, by choosing an appropriately constructed reducing gear drive. However, as the exchanging of reducing gears is cumbersome in gear drives of this kind in which the reducing gears were mounted on horizontal shafts, the machine was usually permanently left in a condition of adjustment appropriate for producing thread intercrossings of the wind spaced apart as far as possible in which way, however, only relatively short lengths of thread can be wound on the winding carrier.

The driving arrangement for thread guides according to this invention permits, by virtue of the worm gear, the speed of revolution of the winding spindle to be transmitted to the traversing member of the thread guide only at a considerably reduced rate so that said member is driven at relatively low speed, while the winding spindle runs at a high speed. Consequently, the thread is wound on the winding carrier at great velocity but distributed by the thread guide relatively slowly so that the thread is crossed only slightly if at all and is thus parallel wound by taking advantage of the feasibility of winding the most part of the various kinds of thread in what may be termed semi or full parallel winds without impairing the thread. By means of exchanging of reducing gears of the gear drive the velocity at which the thread guide is driven can be adjusted more exactly in accordance with the properties of the thread material.

Consequently, this thread guide driving arrangement allows of winding any thread material at a maximum permissible spindle speed and

accordingly of utilizing as completely as possible the efficiency of the machine as well as the capacity of the winding carrier. Due to the relatively slow velocity of the thread guide and of the traversing spindle thereof, on one hand, the thread material is preserved and the formation of fluff reduced, while, on the other hand, the said traversing or guide spindle is axially reciprocated free from shock, so that the setting up of vibrations of the machine is minimized. Since the pair of gears 13, 14 rotates at relatively low speed the driving arrangement runs practically noiselessly.

In the accompanying drawing two embodiments of the invention are illustrated by way of example only, in which

Fig. 1 shows an elevation of a first embodiment with the traversing member in an axial section;

Fig. 2 is a top plan view of Fig. 1, and

Fig. 3 shows an axial section of a second embodiment.

In this instance, the cop winding machine used is provided with a gear box 1 through which passes a winding spindle 2 carrying a coupling member 3 which is rotatably arranged thereon and the hollow shaft of which is firmly connected to the driving disc 4, serving for cooperating with a wedge shaped belt (not shown) which can be actuated from a motor. The coupling member 3 is adapted to cooperate with a mating coupling member 5, which is also carried by the winding spindle 2, and is connected for common rotation with said spindle 2, by means of a spline 6 being arranged in a groove, but so as to be axially displaceable on said spindle by means of an arm 7 which is secured to a control shaft 8 which is in turn controlled by means not shown. The parts 7 and 8 inclusive of accessories are omitted from Fig. 1. A worm 9 is firmly secured to the winding spindle 2 and intermeshes with a worm wheel 10 which is mounted for rotation on a vertical axle pin 11 fixed to the gear box 1. Fig. 3 shows, for the purpose of illustration, the winding spindle 2 to be offset relative to its position in Fig. 2 together with the worm 9. On the axle pin 11 is further mounted a gear 13' which is connected to the worm wheel 10 for conjoint rotation by means of a pin 12. The gear 13' cooperates with a companion gear 14' which is arranged on a vertical axle 15 mounted in the gear box 1.

In the first embodiment (Figs. 1 and 2) the companion gear 14 is coupled, by means of a pin 16, to the hub 17 of a traversing disc 18 which is mounted for rotation on the axle 15 and con-

trols, by means of a circumferential groove, a two-armed rockable lever 19 mounted at 20. The axles 11 and 15 are fixed to the gear box 1. By means of a link 21, to the second arm of the lever 19, a rod 22 displaceably arranged on the machine is attached which carries the thread guide (not shown). The link 21 is adjustably connected with a toothed portion of the lever 19 so that the thread guide carrier rod 22 can be moved through a traverse of greater or shorter length when the traversing member 18 rotates.

In Fig. 2, the conical friction coupling 3, 5 is shown in condition of operation resulting in the rotative movement of the driving disc or pulley 4 being transmitted to the winding spindle 2. The empty spool (not shown) when inserted in the head 2' of the winding spindle is engaged at its second end by a counter holder (not shown). The winding spindle 2 transmits its rotative movement to the gear 13 via the worm drive 9, 10 at considerably reduced speed and thus to the traversing disc 18 via the companion gear 14 by reducing its speed of revolution once more, so that the thread guide carrier rod 22 is accordingly axially reciprocated for the purpose of effecting the cop building operation. By replacing the pair of gears 13, 14 by gears of different diameters the driving speed for the thread guide can be adapted to the thread material. To this end the gears 13 and 14 can be taken off the vertical axles 11 and 15 in the upward direction out of the gear box 1. By this means the replacing of the pair of gears is greatly facilitated, for the reason, that for doing this work ample free space is available above the gear box.

In the second embodiment (Fig. 3), between the worm drive 9, 10 and the traversing disc 18 a second pair of gears 23, 24 is provided, apart from the pair of gears 13, 14, for further reducing the speed of revolution of the traversing disc 18. The gear 23 is firmly keyed to the axle 15, which in this case is rotatably arranged on the gear box 1, and the gear 24 is secured to the hub 17 on the traversing disc 18 which in this instance is rotatably mounted on the axle 11.

As will be readily seen, the arrangement may be such that the gears 23 and 24 also can be replaced, if desired.

In the two embodiments described the worm wheel is arranged in advance, considered with respect to the direction of transmission of the driving movement, of the change speed back gear drive. If required the arrangement may be reversed by arranging the back gear drive in advance of the worm drive.

As shown in Figs. 1 and 2 the drive coupling 3, 5 is protected against the entry of dust, fluff etc. by being housed in a bearing mounting 25 provided on the gear box 1 for the reception of the integral winding spindle 2 carrying the drive coupling 3, 5. This arrangement simplifies the assembling of the drive in true relative position of its parts in adaptation to high driving speeds. During the operation the driving disc 4 carried by the winding spindle 2 is continually driven, whilst by axially shifting one of the halves of the drive coupling 3, 5, being also carried by the winding spindle 2, the disconnecting of the winding spindle 2, that is, the drive coupling is effected. This arrangement results in continuously reliably guiding the displaceable half 5 of the drive coupling.

I claim:

1. In a driving arrangement for a thread guide cooperating with a winding spindle, particularly for cop winding machines, the combination with a thread guide traversing disc rotatable on an axis at right angles to said spindle, a change speed gear drive, including detachably mounted reducing gears drivingly connected between said traversing disc and said winding spindle, of a worm gear operatively connected to said change speed gear drive and said spindle, and a rockable arm operably connected between said disc and the thread guides.

2. In a driving arrangement for a thread guide 15 cooperating with a winding spindle, particularly for cop winding machines, the combination with a thread guide traversing disc rotatable on an axis at right angles to said spindle, a vertical axle change speed gear drive, including detachably mounted reducing gears drivingly connected between said traversing disc and said winding spindle, of a vertical axle worm gear operatively connected to said change speed gear drive and said spindle, and a rockable arm operably connected between said disc and the thread guide.

3. In a driving arrangement for a thread guide 20 cooperating with a winding spindle, particularly for cop winding machines, the combination with a thread guide traversing disc rotatable on an axis at right angles to said spindle, a vertical axle change speed gear drive, including detachably mounted reducing gears drivingly connected between said traversing disc and said winding spindle, of a vertical axle worm gear operatively connected to said change speed gear drive and said spindle, and a rockable arm operably connected between said disc and the thread guide.

30 4. In a driving arrangement for a thread guide cooperating with a winding spindle, particularly for cop winding machines, the combination with a thread guide traversing disc rotatable on an axis at right angles to said spindle, a vertical axle change speed gear drive, including detachably mounted reducing gears drivingly connected between said traversing disc and said winding spindle, of a vertical axle worm gear operatively connected to said change speed gear drive and said spindle, and a rockable arm operably connected between said disc and the thread guide.

45 5. In a driving arrangement for a thread guide cooperating with a winding spindle, particularly for cop winding machines, the combination with a thread guide traversing disc rotatable on an axis at right angles to said spindle, a vertical axle change speed gear drive, including a detachably mounted reducing gear intermeshing with a removable companion gear drivingly connected between said traversing disc and said winding spindle, said companion gear being arranged with said traversing disc on a common vertical axle, of a vertical axle worm gear operatively connected to said change speed gear drive and said spindle, said worm gear being connected with the first-mentioned reducing gear cooperating with the companion gear, and a rockable arm operably connected between said disc and the thread guide.

55 6. In a driving arrangement for a thread guide cooperating with a winding spindle, particularly for cop winding machines, the combination with a thread guide traversing disc rotatable on an axis at right angles to said spindle, a change speed gear drive, including exchangeable reducing gears drivingly connected between said traversing disc and said winding spindle of a worm gear operatively connected to said change speed gear drive and said spindle, means for rotating said winding spindle, said rotation being transmitted to said change speed gear drive via said worm gear, and a rockable arm operably connected between said disc and the thread guide.

70 75 6. In a driving arrangement for a thread guide cooperating with a winding spindle, particularly

for cop winding machines, the combination with a thread guide traversing disc rotatable on an axis at right angles to said spindle, a change speed gear drive, including exchangeable reducing gears drivingly connected between said traversing disc and said winding spindle of a worm gear operatively connected to said change speed gear drive and said spindle, said worm gear being fixedly mounted directly on said winding spindle, means for rotating said winding spindle, said rotation being transmitted to said change speed gear drive via said worm gear, and a rockable arm operably connected between said disc and the thread guide.

7. In a driving arrangement for a thread guide cooperating with a winding spindle, particularly for cop winding machines, the combination with a thread guide traversing disc rotatable on an axis at right angles to said spindle, a change speed gear drive, including exchangeable reducing gears drivingly connected between said traversing disc and said winding spindle of a worm gear operatively connected to said change speed gear drive and said spindle, said worm gear being fixedly mounted directly on said winding spindle, a drive coupling mounted on said integral winding spindle, for rotating said spindle, means for ro-

tating said drive coupling, said rotation of said winding spindle being transmitted to said change speed gear drive via said worm gear, and a rockable arm operably connected between said disc and the thread guide.

8. In a driving arrangement for a thread guide cooperating with a winding spindle, particularly for cop winding machines, the combination with a thread guide traversing disc rotatable on an axis at right angles to said spindle, a change speed gear drive, including exchangeable reducing gears drivingly connected between said traversing disc and said winding spindle of a worm gear operatively connected to said change speed gear drive and said spindle, said worm gear being fixedly mounted directly on said winding spindle, 10 a drive coupling comprising two complementary halves mounted on said integral winding spindle, a driving pulley mounted on said winding spindle, and connected with the driving half of said coupling for rotating said spindle, said rotation of said winding spindle being transmitted to said change speed gear drive via said worm gear, and a rockable arm operably connected between said disc and the thread guide.
